AERODYNAMIC PRESSURE PROBE

Richard V. De Leo, Hopkins, and Floyd W. Hagen, Eden Prairie, Minn., assignors to Rosemont Inc., Eden Prairie, Minn.

Filed Mar. 8, 1971, Ser. No. 122,286

Term of patent 14 years

Int. Cl. D12—99

U.S. Cl. D71—1 D

FIG. 1 is a perspective view of an aerodynamic pressure probe embodying our new design;

FIG. 2 is a side elevational view thereof;

FIG. 3 is a bottom plan view thereof;

FIG. 4 is a top plan view thereof; and

FIG. 5 is a front view thereof.

We claim:

The ornamental design for an aerodynamic pressure probe, substantially as shown.
